UNITED STATES PATENT OFFICE.

WILLIAM HARVEY, OF INDIANAPOLIS, INDIANA.

CARPET-STRETCHER.

SPECIFICATION forming part of Letters Patent No. 498,977, dated June 6, 1893.

Application filed September 3, 1892. Serial No. 445,010. (No model.)

To all whom it may concern:

Be it known that I, WILLIAM HARVEY, of Indianapolis, county of Marion, and State of Indiana, have invented certain new and useful Improvements in Carpet-Stretchers; and I do hereby declare that the following is a full, clear, and exact description thereof, reference being had to the accompanying drawings, in which like figures refer to like parts.

10 My invention relates to improvements in carpet stretchers, and will appear more fully from the following description.

In the drawings, Figure 1 represents my carpet stretcher after it has grasped the carpet. Fig. 2 represents the same in the process of grasping the carpet, the dotted lines showing the position of the parts after the jaws have closed upon the carpet. Fig. 3 represents the same in the latter part of its movement.

20 In detail, 1 represents a carpet.

2 is a foot piece having a spur 3 under its rear end, and pivoted at 4 to the bent lever 5. This bent lever is pivoted at 6 to another bent 25 lever 7, so that the two will operate in different directions.

8 and 9 are jaws of the levers, which have smooth edges 10, and a few spurs 11 set at some distance back from the front edges of 30 the jaws.

12 is a handle connected with the bent lever 7.

The operation of my carpet stretcher is as follows: The stretcher is placed so that the 35 jaw 9 will go under the carpet 1 to be stretched, in the position shown in the heavy lines in Fig. 2. The foot is then placed upon the foot piece 2, driving the spur 3 into the floor, which prevents the stretcher from slipping. The 40 handle is then drawn slightly forward and upward, as shown in dotted lines in Fig. 2, which will cause the jaws 8 and 9 to close upon the carpet, the teeth 11 preventing it from slipping in the beginning of the operation of stretching. The handle 12 is then drawn 45 backward, as shown in Fig. 1. As it is drawn backward, the bent lever 5 turns upon the pivot 4, causing the front edges of the jaws to move from the position shown in Fig. 2 to that 50 shown in Fig. 3. As the handle is operated and the tension of the carpet is increased, the jaws will clamp tightly together. The front

edges of the jaws are made smooth and meet so that after the operation of the stretcher has commenced the jaws will close tighter 55 and tighter upon the carpet as the operation continues and the carpet will be held more by the front edges of the jaws than by the spurs. By this means, as the tension increases, the carpet is not liable to be torn by the teeth, 60 but instead is held by the smooth front edges of the jaws, which hold it tighter and tighter as the handle is drawn farther backward. It will thus be seen that my carpet stretcher is a simple device, easily handled and operated, 55 and stretches the carpet quickly and without tearing it in any way.

The foot, after the spur on the foot piece is pressed down into the floor, can be removed, if desired, as the pressure of the stretcher 70 down upon the other end of the foot piece will hold it down to the floor, and the spur 3 will prevent its slipping. The spur can be located elsewhere under the foot piece, if desired, than at the rear end. The length of the jaws and 75 levers, and points of pivoting the same can be altered to suit the person using the stretcher. The bent lever 5 can be attached to the foot piece 2 by a link instead of a pivot, if desired, but such an arrangement will not operate as 80 well as that shown and described.

What I claim as my invention, and desire to secure by Letters Patent, is the following:

1. In a carpet stretcher, broad jaws adapted to grasp a carpet, such jaws being curved to 85 meet each other and having smooth edges and spurs set back from such edges and adapted to pierce the carpet when the jaws are closed, substantially as described.

2. In a carpet stretcher, a combination of 90 two jaws adapted to grasp a carpet, such jaws formed on pivoted levers crossing each other, the lever on which the lower jaw is formed being extended to form a handle, and means for holding the lever on which the upper jaw 95 is formed to the floor, substantially as described.

3. In a carpet stretcher, the combination of 100 two broad jaws adapted to grasp a carpet, such jaws being curved to meet each other and having smooth edges, and spurs set back from such edges and adapted to pierce a carpet when the jaws are closed, such jaws formed on pivoted levers crossing each other, the le-

ver on which the lower jaw is formed extended to form a handle and means for holding the lever on which the upper jaw is formed to the floor, substantially as described.

5. 4. A carpet stretcher consisting of a foot piece provided with spurs under the same, two broad jaws adapted to grasp a carpet, such jaws being curved to meet each other and having smooth edges, and spurs set back from such edges and adapted to pierce a carpet when the jaws are closed, such jaws formed

on pivoted levers crossing each other, the lever on which the lower jaw is formed extended to form a handle and the lever on which the upper jaw is formed pivoted to such foot piece, 15 substantially as described.

In witness whereof I have hereunto set my hand this 30th day of August, 1892.

WILLIAM HARVEY.
